ABSTRACT OF THE DISCLOSURE

A mechanism having a pair of arms and a pair of links connecting an actuating shaft with a control rod so that rotation of the shaft in a clockwise direction causes the control rod to move longitudinally outward, while counterclockwise rotation of the shaft moves the control rod longitudinally inward, and longitudinal movement of the shaft reverses the mechanism so that clockwise shaft rotation causes inward control rod movement, while counterclockwise shaft rotation results in outward control rod movement.

BACKGROUND OF THE INVENTION**Field of the invention**

This invention relates to a reversing mechanism and more particularly, to a mechanism for translating rotary shaft movement into longitudinal control rod movement that can be reversed upon longitudinal movement of the shaft.

Description of the prior art

Steering of track-type vehicles is achieved by moving one track faster than the other track so that the faster moving track pivots around the slow moving track. Known steering systems for such vehicles have the undesirable feature of steering in an opposite manner when moving in reverse than when moving forward. This creates a certain amount of confusion in training operators since most vehicles steer the same way in reverse as in moving forward. To overcome this steering reversal, it is necessary to reverse the steering control output when the transmission output is reversed.

SUMMARY OF THE INVENTION

An actuating shaft is connected by a first linkage to a control rod so that clockwise rotation of the shaft moves the control rod outward, while counterclockwise rotation of the shaft moves the control rod inward. Upon longitudinal movement of the shaft, the first linkage is disengaged and a second linkage is engaged so that clockwise rotation of the shaft moves the control rod inward, while counterclockwise rotation of the shaft moves the control rod outward. This reversing mechanism enables the steering system of a track-type vehicle to steer the same way when moving in reverse as when moving forward.

BRIEF DESCRIPTION OF THE DRAWING

FIG. 1 is a perspective view of a reversing mechanism embodying the present invention.

FIG. 2 is a vertical section taken on the line 2—2 of FIG. 1 wherein internal parts are shown in side elevation.

FIG. 3 is a section taken on the line 3—3 of FIG. 2.

FIG. 4 is a section taken on the line 4—4 of FIG. 3.

FIG. 5 is an exploded perspective view of the actuating shaft, together with the first and second linkage sleeves that are shown in FIG. 4.

2**DESCRIPTION OF THE PREFERRED EMBODIMENT**

Looking now at FIG. 1, a reversing mechanism 10 is shown having an actuating shaft 12 with a bell crank 14 clamped to one end of the shaft. The bell crank is used to turn the shaft in a clockwise direction as indicated by the arrow 16 or in a counterclockwise direction as indicated by the arrow 18.

Positioned below the bell crank 14 is a support 20 through which the actuating shaft 12 passes and a packing 19 and a bearing 21 are fitted within the support around the actuating shaft. A linkage housing 22 is coupled to the support by machine screws and encloses a portion of the actuating shaft below the support. The linkage housing has a hollow nose portion projecting outward perpendicular to the actuating shaft and this portion of the linkage housing is provided with an upper access cover 24 and a lower access cover 26, as shown in FIG. 2. Machine screws secure the access covers in place and the nose portion of the linkage housing terminates in a parting flange 28 which is adapted to be bolted to adjoining structure, not shown.

An annular collar 30 fits within the center of the parting flange 28 and an O-ring packing 32 fits around the circumference of the collar and forms a seal between the collar and the linkage housing 22. A control rod 34 is slidably fitted through an opening in the center of the annular collar and extends into the interior of the linkage housing where it terminates in a clevis portion 36. The control rod is adapted to slide within the opening in the annular collar in an outward direction, as indicated by the arrow 38, or in an inward direction, as indicated by the arrow 39.

Within the linkage housing 22 is a washer 40 that fits about the actuating shaft 12 beneath the support 20. A first linkage 42 fits about the actuating shaft below the washer and includes a sleeve 44 having an axial opening 46, shown in FIG. 5, to receive the actuating shaft and a groove 48 that extends radially outward from the axial opening and tapers in width upwardly from the lower portion of the sleeve. An arm 50 (FIGS. 2 and 3) projects radially outwardly from the lower portion of the sleeve and a link 51 is pivotably connected to the outer portion of the arm by a bolt 49 and a nut 47.

A washer 52 fits about the actuating shaft 12 below the first linkage 42 and a second linkage 53 fits about the actuating shaft below the washer. The second linkage includes a sleeve 54 having an axial opening 56, shown in FIG. 5, to receive the shaft and a groove 58 that extends radially outward from the axial opening and tapers in width downwardly to the lower portion of the sleeve. An arm 60 projects radially outward from the upper portion of the sleeve 54 and a link 61 (FIGS. 2 and 3) is pivotably connected to the outer portion of the arm by a bolt 62 having a nut 63. Ends of the links 51 and 61 opposite from the arms 50 and 60 are connected to the clevis portion 36 of the control rod 34 by a pin 64 that is held in place by a cotter pin 65.

A lug 66, as shown in FIG. 5, projects outwardly from the actuating shaft 12 and tapers in circumferential width from a maximum at the approximate mid-point MP of the lug, longitudinally along the shaft to a minimum at each end E of the lug. Thus, it will be seen that the upper portion of the lug is tapered to fit within the groove 48, while the lower portion of the lug is tapered to fit within the groove 58. The actuating shaft is moveable longitudinally in an upward direction, as indicated by arrow 67, and in a downward direction, as indicated by the arrow 69. The length L of the lug enables it to fit entirely within one of the grooves so that when the lug engages one sleeve, the other sleeve will be disengaged.

At the lower portion of the linkage housing 22 is a hydraulic cylinder 68 that moves the actuating shaft 12 longitudinally between an upper position for lug 66 to engage sleeve 44 and a lower position for the lug to engage sleeve 54. The hydraulic cylinder includes an intermediate support 70, a body 72, and a cap 74 that are held in place by bolts 76 extending through the cap and intermediate support into the linkage housing.

A washer 77 fits around the actuating shaft 12 between sleeve 54 and intermediate support 70. A bearing 78 and a packing 79 are fitted around the actuating shaft within the intermediate support and the center bore within the support is stepped to form a guide seat 80 and a spring seat 81. A fluid supply line fitting 82 is threadably fitted through the intermediate support from outside thereof to the center bore at a location between the guide seat and the spring seat. A chamber 83 is formed within the body 72 and the actuating shaft extends through this chamber.

A helical compression spring 84 is fitted around a guide 85 that is held in place near the end of the actuating shaft 12 between a stop 86 and a hydraulic piston 87. A seal 88 is fitted around the outer circumference of the hydraulic piston to contact the inner surface of the chamber 83. A guide 89 is held in place between the opposite side of the piston and a stop 90 that is secured on the end of the actuating shaft by a nut 92. A helical compression spring 91 fits around the guide 89 and seats upon a spring seat 93 that is formed within the cap 74. A center bore further extends into the cap from the spring seat to a guide seat 94 and a fluid supply line fitting 95 is threadably fitted through the cap from outside thereof to the center bore, between the guide seat and the spring seat. A nut 96 holds the fluid supply line fitting in place on the cap and a similar nut 97 holds the fluid supply line fitting 82 in place on the intermediate support 70. These nuts are secured by a wire 98 that passes through each nut and interlocks them together so as to prevent rotation.

In operation, the reversing mechanism 10 can be installed in the steering system of a track-type vehicle so that the operator controls the bell crank 14 and the control rod 34 operates the steering system. Fluid supply line fittings 82 and 95 are connected to a transmission hydraulic system of the vehicle that causes forward and reverse clutches to be engaged. When the vehicle is moving forward, hydraulic fluid forces piston 87 upward so that lug 66 fits entirely within the groove 48 of sleeve 44. When bell crank 14 causes the actuating shaft 12 to turn in clockwise direction, the lug engages the sleeve and arm 50 turns clockwise pulling link 51 and control rod 34 inwardly, as indicated by the arrow 39 in the FIG. 1. Since sleeve 54 is disengaged from the lug, arm 60 is free to rotate on the actuating shaft and inward movement of the control rod causes the link 61 to move the arm 60 in a counterclockwise direction. When the bell crank moves the actuating shaft in a counterclockwise direction, arm 50 forces link 51 to move the control rod 34 outward as indicated by the arrow 38.

When the vehicle is in reverse, the hydraulic system causes fluid to flow through the fitting 82 into chamber 83, forcing piston 87 into the position as shown in FIG. 2. Lug 66 is then disengaged from sleeve 44 and engages the sleeve 54 within the groove 58. Clockwise rotation of the actuating shaft 12 causes sleeve 54 to move clockwise and arm 60 forces the link 61 to move control rod 34 in an outward direction, as indicated by the arrow 38 in FIG. 1. Counterclockwise rotation of the actuating shaft causes the arm 60 to draw the link 61 and the control rod 34 inward, as indicated by the arrow 39. Actuating arm 50 and link 51 move with the control rod since the sleeve 44 is disengaged.

From the above description, it will be seen that the reversing mechanism 10 reverses the input forces to the control rod when the transmission output of the vehicle is reversed. It should further be noted that the lug 66 is

always contained within the mating grooves 48 and 58 so that steering control is never lost so long as the vehicle is either moving forward or in reverse. Shifting from forward to reverse while the steering wheel is turned causes reversing rotation of the arms 50 and 60 by sliding on the helical tapered edges of the lug which mate with the edges of the grooves. Thus, the vehicle will turn back on the same track as in making a forward turn without moving the steering wheel and this enables the steering wheel to maintain control over the steering system.

When the vehicle is in neutral, the fluid pressure in the hydraulic supply lines is equal and helical springs 84 and 91 force the piston 87 into an intermediate position. The lug 66 moves into a position between sleeve 44 and sleeve 54, as shown in FIG. 4. In this position, the lug has no effect upon the steering because rotational force in either direction would cause links 51 and 61 to act opposite to each other and thereby balance out any effect on the control rod 34.

Although the best mode contemplated for carrying out the present invention has been herein shown and described, it will be apparent that modification and variation may be made without departing from what is regarded to be subject matter of the invention as set forth in the amended claims.

Having completed a detailed description of the invention so that those skilled in the art could practice the same, I claim:

1. A reversing mechanism comprising an actuating shaft mounted for longitudinal movement in upward and downward directions and for rotational movement about its longitudinal axis in clockwise and counterclockwise directions; a control rod mounted perpendicular to the shaft for movement longitudinally in outward and inward directions; a first linkage connected to the control rod and engageable with the shaft to move the control rod outward in response to clockwise rotation of the shaft and inward in response to the counterclockwise rotation of the shaft; a second linkage connected with the control rod and engageable with the shaft to move the control rod outward in response to counterclockwise rotation of the shaft and inward in response to clockwise rotation of the shaft; a lug projecting from the shaft to engage either said first or said second linkage; and means for moving the shaft longitudinally to position the lug in engagement with either said first or said second linkage.

2. A reversing mechanism as defined in claim 1 wherein said first linkage includes a sleeve having an axial opening to receive the shaft and a groove extending radially outward from the axial opening to receive the lug on the shaft, an arm projecting radially outward from the sleeve, and a link pivotably connected to the arm and to the control rod; and said second linkage includes a sleeve having an axial opening to receive the shaft and a groove extending radially outward from the axial opening to receive the lug on the shaft, an arm projecting radially outward from the sleeve, and a link pivotably connected to the arm and to the control rod; said second linkage being spaced longitudinally along the shaft from the first linkage.

3. A reversing mechanism as defined in claim 2 wherein the lug tapers in width from its approximate midpoint longitudinally along the shaft to opposite ends; and the grooves within each sleeve have their largest width dimension at the abutting ends of the sleeves and taper to the opposite ends thereof.

4. A reversing mechanism as defined in claim 3 wherein the means for moving the shaft axially include a hydraulic piston fitted about one end of the shaft and a hydraulic cylinder fitted about the hydraulic piston, a first hydraulic fluid supply line connected to the hydraulic cylinder on one side of the piston, and a second hydraulic fluid supply line connected to the hydraulic cylinder on the opposite side of the piston from the first hydraulic fluid supply line, said hydraulic fluid supply lines being

adapted to be connected to a hydraulic system that controls the hydraulic cylinder.

5. A reversing mechanism as defined in claim 2 where-
in the arms of said first and second linkages project out-
ward toward opposite sides of the control rod.

6. A reversing mechanism as defined in claim 5 where-
in the arms of said first and second linkages are of equal
length and the links of said first and second linkages are
of equal length.

7. A reversing mechanism as defined in claim 6 where-
in the links of said first and second linkages are pivotably
connected to the control rod on a common pivotal axis
parallel with the actuating shaft.

8. A reversing mechanism comprising:
an actuating shaft mounted for rotational movement
about its longitudinal axis in clockwise and counter-
clockwise directions;
a control rod mounted perpendicular to the actuating
shaft for longitudinal movement inward and outward
therefrom;
15 first means connected to the control rod and engage-
able with the actuating shaft for moving the control
rod outward in response to clockwise rotation of the
shaft and inward in response to counterclockwise
rotation of the shaft;
second means connected to the control rod and engage-
able with the actuating shaft for moving the control
rod outward in response to counterclockwise rotat-
ion of the shaft and inward in response to clockwise
rotation of the shaft; and
means for engaging the actuating shaft selectively with
either said first or second means connected to the
control rod.

9. A reversing mechanism as described in claim 8

wherein said actuating shaft is mounted for longitudinal
movement and said means for engaging the actuating shaft
selectively with either said first or second means connected
to the control rod is positioned for engagement by longi-
tudinal movement of the actuating shaft.

5 10. A reversing mechanism as described in claim 9
wherein said means for engaging the actuating shaft selec-
tively with either said first or second means connected to
the control rod can be positioned between engagement pos-
itions by longitudinal movement of the actuating shaft
and in such intermediate position said mechanism is in-
operative for translating rotational movement of the act-
uating shaft into longitudinal movement of the control
rod.

11. A reversing mechanism as described in claim 10
including hydraulic means responsive to fluid pressure in
one direction for moving the actuating shaft to an en-
gagement position with the first means connected to the
control rod and responsive to fluid pressure in an oppo-
site direction for moving the actuating shaft to an en-
gagement position with the second means connected to the
control rod; and resilient means for positioning the
actuating shaft with the engaging means intermediately of
engagement positions when fluid pressure in both direc-
20 25 tion is equalized.
